INVENTOR

Herbert Cottrell

UNITED STATES PATENT OFFICE.

HERBERT COTTRELL, OF NEWARK, NEW JERSEY, ASSIGNOR TO L. A. SAYRE & CO., OF NEWARK, NEW JERSEY, A FIRM.

SAW-SET.

SPECIFICATION forming part of Letters Patent No. 731,864, dated June 23, 1903.

Application filed December 2, 1902. Serial No. 133,541. (No model.)

To all whom it may concern:

Be it known that I, HERBERT COTTRELL, of the city of Newark, county of Essex, State of New Jersey, have invented certain new and useful Improvements in Saw-Sets, of which the following is a specification.

The object of my invention is to provide a saw-set adapted to set two teeth of a saw oppositely at the same time constructed of such simple parts as to be produced cheaply.

My invention consists in constructing a saw-set of upper and lower handle members, the upper handle having the body and frame integral therewith and the lower handle forming the operating-lever.

It also consists in a longitudinally-operative slide-block forming a beveled anvil and a flat clamp and carrying a detachable set-point, which projects from the base of the beveled face thereof, below which the slide-block presents a flat transverse clamping-surface, and, further, it consists in an opposed slide-block which also forms a beveled anvil and flat clamp and carries a detachable set-point and which is adapted to be moved transversely by means of a screw-threaded shaft, both slide-blocks having projecting flanges extending outwardly beneath the frame, which forms a guide and sliding support for the same.

In the accompanying drawings, which form part of this specification, Figure 1 is a side view. Fig. 2 is a plan view. Fig. 3 is a longitudinal sectional view embodying my invention, in all of which like letters of reference refer to similar parts.

Referring to Figs. 1 to 3, inclusive, *a* shows the upper handle member, having handle, body, and frame integral. *b* shows the lower handle member, forming the operating-lever. *c* is the pivot-fulerum. *d* is longitudinal thrust-shaft; *e*, stop-pin; *f*, spiral retractile spring; *g*, longitudinally-operative slide-block, showing projecting guides at base in dotted lines; *h*, transversely-adjustable slide-block, showing supporting-guide at base; *i* and *j*, oppositely-projecting detachable set-points; *k*, transverse adjusting-screw; *l*, open-

ing between parallel clamping-faces of slide-blocks; *m*, tilting frame to adjust depth of tooth; *n*, tilting-frame-adjusting screw; *o*, 50 tilting-frame side lugs to rest against saw-teeth; *p*, nut on end of adjusting-screw; *q*, milled head of adjusting-screw.

The operation is as follows: The saw-blade is inserted in opening *l* between slide-blocks *g* and *h*. The depth of tooth is adjusted by means of tilt-frame *m* and the width of tooth gaged by adjusting set-points *i* and *j* to the proper distance apart. Pressure upon lower lever-handle *b* causes thrust-shaft *d* and slide-block *g* to move longitudinally toward slide-block *h* and causes set-points *i* and *j* to each press a saw-tooth oppositely upon the beveled surfaces of anvils *g* and *h*, the saw-blade being held transversely square between the flat 65 clamping-faces of *g* and *h*. Releasing pressure upon lever *b* permits spiral spring *f* to again separate the blocks *g* and *h*, and thus successively two teeth may be set at the same time.

The simplicity of structure, the rigidity of action of slide-blocks and set-points gained through their guide-supports, and the perfect transverse adjustment of the set-points by means of screw-shaft distinguish my invention from other implements of the same class.

What I claim, and desire to secure by Letters Patent of the United States, is—

In a saw-set comprising a handle-frame a longitudinally-operative slide-block, and an 80 opposed slide-block carried upon and adjustably operated transversely by a screw-shaft; both slide-blocks provided with inclined anvil-faces, vertical clamping-faces, and flanged supporting-guides; in combination with projecting set-points removably held by the said slide-blocks, substantially as described.

In witness whereof I have subscribed my name hereto this 29th day of November, 1902.

HERBERT COTTRELL.
